UNITED STATES PATENT OFFICE.

BEVERLEY R. DUDLEY, OF RICHMOND, VIRGINIA.

DESIGN FOR A WHIRLIGIG-WHEEL.

SPECIFICATION forming part of Design No. 23,089, dated February 27, 1894.

Application filed January 27, 1894. Serial No. 498,258. Term of patent 7 years.

To all whom it may concern:

Be it known that I, BEVERLEY R. DUDLEY, a citizen of the United States, residing at Richmond, in the county of Henrico and State of Virginia, have invented a new and original Design for Whirligig-Wheels, of which the following is a specification, reference being had to the accompanying drawings, and to the letters of reference marked thereon.

Figure 1 is a plan view and Fig. 2 an edge view; which figures fully illustrate my design.

The leading feature of my design consists of a central disk having arranged radially around its periphery a series of figures of children joined hand to hand.

A is the central disk and B B are the figures arranged radially with relation thereto,

the feet of the figures joining its circumference.

The figures B are joined hand to hand as at 20 a, and they and the central disk A occupy a common plane, as shown in Fig. 2.

What I claim is—

The design for a whirligig wheel herein shown and described, the same comprising the 25 central disk A, and the series B B of figures of children arranged radially thereof, the said figures being joined hand to hand, as set forth.

In testimony whereof I hereto set my hand and seal.

BEVERLEY R. DUDLEY. [L.S.]
